UNITED STATES PATENT OFFICE.

ARTHUR TREVOR DAWSON AND GEORGE THOMAS BUCKHAM, OF WESTMINSTER,
LONDON, ENGLAND, ASSIGNORS TO VICKERS LIMITED, OF WESTMINSTER,
LONDON, ENGLAND.

LOCK MECHANISM OF BREECH-LOADING GUNS.

1,302,518.

Specification of Letters Patent.

Patented May 6, 1919.

Application filed April 13, 1915. Serial No. 21,120.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Lock Mechanism of Breech-Loading Guns, of

10 which the following is a specification.

This invention relates to lock mechanism of the kind in which a primer magazine or hopper occupies a stationary position at one side of the vent axial and the lock frame has 15 a mouth or opening formed in it above the forward portion of the bolt sleeve so that when the lock frame is moved into its fully open position, the bolt sleeve will lie beneath the exit opening of the magazine or 20 hopper from which a primer will fall through the mouth or opening in the lock frame on to the top of the bolt sleeve.

According to the present invention the primer magazine or hopper is arranged in 25 such a position that its outlet opening is situated above and at one side of the bolt sleeve when the lock frame is in its fully open position so that although a primer can descend through the mouth or opening in 30 the lock frame to rest on the forward part of the bolt sleeve, it can not enter the outlet opening of the hopper as a result of the slamming of the breech screw carrier and cannot thereby prevent the lock frame from 35 being closed, since when the primer "jumps" during the slamming of the carrier, it will bear against the portion of the box slide that is above the bolt sleeve and contiguous to the said outlet opening.

40 In order that the said invention may be clearly understood and readily carried into effect, we will describe the same more fully with reference to the accompanying drawings, in which:—

45 Figure 1 is a sectional rear elevation showing in a more or less diagrammatic manner a constructional form of our improvements, the parts being in the position they occupy when the lock frame is closed and the bolt 50 locked.

Fig. 2 is a view similar to Fig. 1 showing the position of the parts when the lock frame is open,

Fig. 3 is a similar view but with the lock frame closed and the bolt still in the locked 55 position, and

Fig. 4 is also a similar view but with the lock frame closed and the bolt withdrawn and ready to insert the primer.

A is the lock frame carrying the bolt A'. 60 B is the box slide supporting the hopper B'.

The hopper, which contains a single row of primers, is mounted in such a position that its exit opening is situated at a greater lateral distance from the axis of the axial 65 vent than is the axis of the bolt when the lock frame is open (see Fig. 2). The opening B² in the box slide through which the primers fall is slightly inclined laterally toward the axial vent. The right hand edge 70 of the mouth or opening A² in the lock frame which is farthest from the axial vent when the frame is open is inclined at a and then serves both to guide the falling primer into the mouth or opening (Fig. 2) and to force 75 the primer next above the one referred to, back into the hopper during the closing of the lock frame (Fig. 3). The under surface of the box slide is cut away as shown at b as far as or beyond a vertical plane 80 containing the axis of the gun to prevent the primer from jamming between the inclined face a of lock frame and the box slide. In other respects the lock mechanism is similar 85 to that set forth in our aforesaid prior specification.

What we claim and desire to secure by Letters Patent of the United States is:—

1. In the lock mechanism of ordnance, the combination with the rectilinearly and laterally moving lock frame and the bolt sleeve carried thereby, of a stationary 90 primer magazine so positioned that its outlet opening is situated at one side of the bolt sleeve when the lock frame is in its 95 fully open position.

2. In the lock mechanism of ordnance, the combination with the rectilinearly and laterally moving lock frame and the bolt sleeve carried thereby, of a stationary magazine so positioned that its outlet opening is situated at one side of the bolt sleeve when the lock frame is in its fully open position, and inclined surfaces for guiding the primers from the magazine onto the bolt 105 sleeve.

3. In lock mechanism of ordnance, the combination with the lock frame, the bolt sleeve carried thereby and the box slide in which said lock frame is slidably mounted, 5 said lock frame and box slide having openings therein, of a stationary primer magazine so positioned that its outlet opening is situated at one side of the bolt sleeve when the lock frame is in its fully open position, 10 and inclined surfaces in the openings in the lock frame and box slide for guiding the primers from the magazine onto the bolt sleeve.
4. In lock mechanism of ordnance, the combination with the lock frame, the bolt sleeve carried thereby and the box slide in which said lock frame is slidably mounted, said lock frame and box slide having openings therein; of a stationary primer magazine containing a single row of primers, said 20 magazine being so positioned that its outlet opening is situated at one side of the bolt

sleeve when the lock frame is in its fully open position.

5. In lock mechanism of ordnance, the combination with the lock frame, the bolt sleeve carried thereby and the box slide in which said lock frame is slidably mounted, said lock frame and box slide having openings therein; of a stationary primer magazine so positioned that its outlet opening is situated at one side of the bolt sleeve when the lock frame is in its fully open position, the undersurface of said box slide being cut away for a distance extending from the 30 opening in the box slide to a vertical plane containing the axis of the gun.

In testimony whereof we affix our signatures in the presence of two witnesses.

ARTHUR TREVOR DAWSON.
GEORGE THOMAS BUCKHAM.

Witnesses:
